PIPE WRENCH

William O. Thewes, North Ridgeville, Ohio, assignor to The Ridge Tool Company, North Ridgeville, Ohio, a corporation of Ohio

Application September 9, 1932. Serial No. 632,321

13 Claims. (Cl. 81—101)

This invention relates broadly to wrenches and particularly to pipe wrenches, and the primary object of the same is to provide an advantageous type of guide mounting for the shank of the 5 movable jaw of a pipe wrench which will always maintain the said jaw and shank in a freely-slidably substantially neutral position in the housing or yoke member therefor.

Another object is to provide a cooperating 10 housing and guide construction for the movable jaw and shank of a pipe wrench which will always maintain the said jaw and shank in a neutral freely-sliding position in the yoke member of a jaw housing while at the same time permitting the jaw to have a certain amount of 15 resilient angular movement relative to the fixed jaw so that the jaws may be more readily fitted to the work and firmly grip the latter without slipping.

Another object is to provide a guide mounting 20 for the movable jaw of a pipe wrench which is an improvement over prior known mountings and which at the same time is simple in design and does not complicate formation of the yoke 25 member or jaw housing.

With the foregoing and other objects and advantages in view, the invention consists in the preferred construction and arrangement of the several parts which will be more fully herein- 30 after described and claimed.

In the drawing:—

Figure 1 is a view principally in side elevation with the yoke member or jaw housing broken away in part to show the method of mounting 35 said jaw;

Fig. 2 is a detail view of one of the parts;

Fig. 3 is a sectional view taken on the line 3—3, Fig. 1;

Fig. 4 is a fragmentary sectional view of the 40 housing and fixed jaw portion of the wrench, showing a modified type of spring member, and Fig. 5 is a detail view of said member;

Figs. 6 and 7 are, respectively, views similar to Figs. 4 and 5 of a further modified form of 45 spring mounting;

Fig. 8 is a view in sectional side elevation of a still further modification in structure; and

Fig. 9 is a view taken on the line 9—9, Fig. 8.

Referring in detail to the drawing, the reference numeral 5 designates the handle portion of the wrench and 6 the fixed jaw portion having removably fixed thereon, by means of pin 7, a jaw plate 8. The movable jaw is indicated at 9 and is formed with the usual threaded shank 10 55 which is adapted to move longitudinally in the

yoke member or housing 11. The handle portion 5 is preferably formed with a boss or projection 12, and an adjusting nut 13 is threaded on the shank 10 and is positioned between the said boss and housing. 60

The side walls of the housing 11 at the base of the latter are formed with a longitudinal slot 15, note particularly Fig. 3, defining stop shoulders 16. In this slotted portion a resiliently-mounted guide 17 is positioned and preferably 65 extends longitudinally for the full length of the housing. In the form shown in Figs. 1, 2 and 3, the guide 17 is provided with a retainer toe 17a which projects into a recess 18 formed between the jaw plate 8 and the end of the portion 6 70 of the wrench. Spring-housing bores 19 are formed in the portion 6, and therein springs 20 are positioned and bear against the guide 17, urging the latter against the stop shoulders 16. The bores 19 preferably extend at converging 75 angles, to permit a tool to clear the housing 11 when the bores are formed.

The back wall of the housing 11 is given a slight taper from an intermediate point toward the forward end of the housing, as at 21, while 80 from this point toward the rear of the housing said wall is substantially straight, as at 21a. Thus, at the rear portion of the housing, the shank 10 of the movable jaw has a fairly snug sliding fit, sufficient clearance being permitted by 85 the spring pressed guide 17 so as not to hinder the freedom of action of said shank, while at the forward portion of said housing, the tapered wall permits a certain additional limited rocking motion under tension of the shank when the 90 jaws grip the work.

The advantages of the foregoing construction will be readily apparent to those familiar with wrenches of this type. The spring-pressed guide 17 gives the shank 10 of the movable jaw 95 9 a fairly snug sliding fit in the housing 11 without exerting any binding action or pressure thereon, since outward movement of said guide is limited by the stop shoulders 16, while at the same time the taper 21 in conjunction with the guide permits a certain amount of resilient rocking movement of the movable jaw 100 relative to the fixed jaw so that the jaws can be more readily fitted to the work and exert a firm grip on the latter without slipping. The jaws are always in the most favorable position to be adjusted to the work, and the adjusting nut can be manipulated without any binding action whatsoever. Another advantage is that the 105 guide mounting requires no recessing or diffi- 110

cult machining or boring operations in the side walls of the housing, which has to stand heavy duty and is generally made of forged and hardened metal, so that said housing can be pierced 5 hot on a forging machine. The guide 17 is simple in construction and may be made from suitable sheet metal stamping. The body of the guide is preferably given an arcuate contour in cross section, to conform to the shape of the 10 shank 10.

In Figs. 4 and 5, a modified type of guide is shown and consists of a piece of sheet metal having cut or stamped from the middle thereof spring legs 17b, the forward leg being formed 15 with the retaining toe 17a. The side strips 17c which remain after formation of the spring legs 17b form the bearing portion of the guide. This type of guide eliminates formation of the bores 19 and is in one piece only.

20 In Figs. 6 and 7, the guide has retaining lugs or projections 17d stamped from the central portion thereof leaving the bearing or body portion 17e. These lugs or projections 17d engage in the springs 20 positioned in the bores 19.

25 In Figs. 8 and 9, the guide is mounted in the back wall of the housing which is formed with the longitudinal slot 15. The guide is indicated at 17f and has stamped out or otherwise formed on the intermediate portion thereof projections 17g which extend into a recess 19a formed in the back of the housing. A spring 20a is positioned in the recess around the projections 17g and maintains the guide under tension, urging it against the stop shoulders 16 of 30 the slot 15. In this construction, the taper 21 may be omitted.

In each form shown, the guide is limited in its outward movement with respect to the shank 10 of the movable jaw 9 so that the said shank 40 is always maintained in a substantially parallel or neutral freely-sliding position with respect to its housing 11.

It will be understood that certain structural variations and modifications may be adopted 45 within the scope of the appended claims without departing from the spirit of the invention.

I claim:—

1. A wrench comprising a fixed jaw and a movable jaw having a shank, a housing for said shank, and a resiliently-mounted member in said housing having restricted movement toward the shank to maintain the latter in a substantially neutral freely-sliding position in the housing without actually exerting pressure on the 55 shank.

2. A wrench comprising a fixed jaw and a movable jaw having a shank, a housing for said shank, a resiliently mounted guide member in said housing, and means for limiting the movement of said guide member toward said shank to give the shank a freely-sliding neutral mounting in the housing, while permitting a certain amount of rocking movement of the shank under tension.

65 3. A wrench comprising a fixed jaw and a movable jaw having a shank, a housing for said shank formed with a tapered back wall, a spring-pressed guide member in said housing, and means for limiting the movement of said 70 member toward the shank.

4. A wrench comprising a fixed jaw and a movable jaw having a shank, a housing for said shank, a spring-pressed guide member in said housing, means for limiting movement of said 75 member toward the shank to maintain the latter

in a substantially neutral position in the housing, and a partly tapered back wall on said housing to permit limited angular movement under tension of the movable jaw relatively to the fixed jaw.

5. A wrench comprising a fixed jaw and a movable jaw having a shank, a housing for said shank, a partly tapered back wall on said housing, and a resiliently-mounted guide member in said housing having limited movement toward said shank.

6. A wrench comprising a fixed jaw and a movable jaw having a shank, a housing for said shank, a spring-pressed guide member in said housing, and stop shoulders against which said member abuts, said shoulders being positioned so that the guide member and housing form a relatively snug sliding fit for the shank without exerting a bearing pressure thereon.

7. A wrench comprising a fixed jaw and a movable jaw having a shank, a housing for said shank, and a spring-pressed guide member in said housing, said guide member being housed in a cavity formed with stop shoulders which limit the movement of the guide member toward 100 said shank, to provide a relatively snug sliding fit for the shank without exerting a bearing pressure thereon.

8. A wrench comprising a fixed jaw and a movable jaw having a shank, a housing for said 105 shank, the body portion of the wrench adjacent the fixed jaw being formed with a longitudinally-extending cavity formed with stop shoulders, a spring-pressed guide member in said cavity adapted to abut against said 110 shoulders to provide a relatively snug sliding fit for said shank without binding the latter, and a partly tapered back wall formed on said housing.

9. In a pipe wrench, a movable jaw formed 115 with a shank, a housing for said shank, a resiliently-mounted member having limited movement toward said shank to provide a relatively snug sliding fit for the shank and maintain the latter in a substantially neutral position 120 in the housing, and a partly tapered back wall on said housing to permit limited angular movement of said jaw when applied to work.

10. In a pipe wrench, a fixed jaw and a movable jaw formed with a shank, a housing for 125 shank, a spring-pressed guide member mounted in the base of said housing, means for limiting the movement of said guide member toward said shank, and means for retaining said member against longitudinal displacement in 130 the base of said housing.

11. In a pipe wrench, a fixed jaw portion formed with a housing, a movable jaw formed with a shank adapted to have longitudinal movement in said housing, a spring-pressed 135 guide member for said shank mounted in said housing and extending for substantially the full length of the housing, stop shoulders for limiting the movement of the guide member toward said shank to give the latter a relatively snug 140 sliding fit in the housing without exerting bearing pressure on the shank to thereby maintain the latter in a freely-sliding neutral position in the housing, the back wall of the housing being partly tapered from the rear toward the front 145 thereof to permit limited angular movement of the movable jaw relatively to the fixed jaw.

12. In a pipe wrench, a movable jaw and a fixed jaw, a housing for the shank of the movable jaw, a recess formed in the back wall of 150

15 said housing, a longitudinal slot extending at substantially right angles to said recess defining stop shoulders, a guide member mounted in said slot, and a spring mounted in said recess for normally urging said guide member against said stop shoulders.

13. A pipe wrench comprising a fixed jaw portion formed with a handle and a housing, a movable jaw formed with a shank adapted to 10 have longitudinal movement in said housing, the base of said housing being formed with a longitudinal slot, a spring-pressed guide member for

80 said shank mounted in said slot, the side walls of said slot terminating in ledges against which said guide member abuts to thereby limit the movement of said member toward the shank and give the latter a relatively snug sliding fit in the housing without exerting bearing pressure on the shank, the back wall of the housing being tapered from an intermediate point to the front thereof to permit limited angular or rocking movement of the movable jaw relatively to the fixed jaw.
